United States Patent Office

Des. 229,392

Patented Nov. 27, 1973

229,392

CLAMP OR SIMILAR ARTICLE

Emil Faust, Highland Park, Ill., assignor to Burwood Products Company, Chicago, Ill.

Filed Oct. 15, 1971, Ser. No. 189,805

Term of patent 14 years

Int. Cl. D8—08

U.S. Cl. D8—233

FIG. 1 is a perspective view of an assembled clamp, or similar article, showing my new design; and

FIG. 2 is a perspective view, similar to FIG. 1 but showing the clamp, or similar article, of the invention with its two cooperating elements separated.

I claim:

The ornamental design for a clamp or similar article, as shown.
